UNITED STATES PATENT OFFICE.

ELMER V. GRIGGS, OF WHITE PLAINS, NEW YORK, ASSIGNOR TO WESTERN ELECTRIC COMPANY, INCORPORATED, OF NEW YORK, N. Y., A CORPORATION OF NEW YORK.

WAVE-TRANSMISSION SYSTEM.

Application filed February 17, 1922, Serial No. 537,156. Renewed June 2, 1925.

To all whom it may concern:

Be it known that I, ELMER V. GRIGGS, a citizen of the United States, residing at White Plains, in the county of Westchester, 5 State of New York, have invented certain new and useful Improvements in Wave-Transmission Systems, of which the following is a full, clear, concise, and exact description.

10 This invention relates to wave transmission systems and more particularly to transmission of the energy of given waves or impulses by means of waves of lower frequency than those whose energy is to be transmitted.

15 An important field of electric transmission is that involving the use of unidirectional or alternating currents modified in certain of their characteristics, such as continuity, intensity or frequency. In this field, which

20 includes electric signaling and other teledynamic electric operation, efficiency from an energy standpoint is important but is frequently much less important than faithful transmission of the wave forms involved.

25 In the case of telephony there is involved transmission of a wide range of essential frequencies and for certain circuits, such as those of submarine cables, the distance to which such transmission may be had is limited

30 because of the difference in transmission of the various frequency components involved. Various expedients have been resorted to in an attempt to improve the transmission of such circuits for the higher frequencies.

35 frequency components and to equalize the attenuation experienced by the different frequency components. These expedients in general involve change in the characteristics of the transmission circuit itself or special

40 terminal apparatus associated therewith. From a practical standpoint loading of the circuit, particularly in the case of submarine circuits is feasible only for limited distances. Inductance loading which is commonly em-

45 ployed for such circuits also imposes an upper frequency limit upon the transmission range of the circuit lower than that possessed by the unloaded circuit. Attenuation equalization may be resorted to in lieu of

50 loading in order to reduce each of the components after transmission to the same proportional amplitude which they had before transmission. This requires elaborate terminal apparatus and high amplification and

55 is moreover subject to the difficulty that any

disturbance or interference is likewise highly magnified in the amplifying system. The method of the present invention attacks the problem from the standpoint of reduction of the effective frequencies of the currents to be transmitted so that they may be transmitted over circuits of limited frequency range. This principle of frequency reduction may be used alone or in conjunction with the expedients previously known in the art, such as loading and attenuation equalizers.

Since transmission of speech involves waves extending throughout a wide band of frequencies, it is necessary, if the intelligibility and naturalness of the speech are to be preserved to make the transmission such as to retain each of the initial frequency elements. Where the highest essential frequency elements exceed the upper limit of the frequency transmission range of the circuit, successful transmission thereover is not possible. An object of the present invention is to effectively reduce the frequencies of the various components of a band of currents so as to make them fall within the transmission range of commercial transmission circuits.

With this general view of the problem involved the principles of the invention may be outlined. Assume that a band of currents ranging from a definite lower frequency up to a fixed upper frequency is to be transmitted. According to the present invention there is subtracted from the frequency of each component of the band the frequency of the lowest frequency component. The band remains of the same extent but its lower frequency limit has become zero and its upper frequency limit has been so reduced that the band may fall within the transmission range of a circuit which could not successfully transmit the original band. After transmission over the circuit the frequency of each component is augmented by the original lower limiting frequency and the components are thus restored to their original frequency position.

If the original band, which it is desirable or necessary to transmit, is not continuous, but consists of a number of smaller subbands separated by blank or unessential frequency intervals, the operation upon the lowest frequency subband will obviously be to subtract from the frequency of each of its components

the original frequency of its lowest frequency component. This operation reduces the first or lowest frequency subband to a range from zero to a new upper limiting frequency. There may be subtracted from the frequency of each component of the second or next highest subband a frequency sufficient to reduce its lowest frequency component to approximately the new upper limiting frequency of the first subband. The third subband is similarly reduced in frequency so as to make its lowest frequency approximately that of the highest frequency of the reduced second band. This procedure is repeated with each subband in turn and the final result is a continuous band from zero to a fixed upper limit. This continuous band may be transmitted and, after transmission, may be separated into its various subbands, and each subband may be stepped up in frequency to its original frequency position.

It may happen with the original band reduced in frequency in the manner just described to a continuous band extending up from zero frequency, that its upper limiting frequency is still outside the frequency transmission range of circuits commercially available. In this case instead of reducing the entire band to one continuous band, each of the original subbands may be treated independently and reduced in frequency by the original frequency of its own lowest component. There will result a number of subbands each extending from zero frequency up and each may be transmitted over an individual transmission channel or circuit. The number of subbands and channels will be the same and if this number is made sufficiently large the highest frequency of the original band may be reduced to any desired degree. After transmission over their separate channels each of the various subbands may be stepped up to its original frequency position, and the bands may then be reassembled to reproduce the original band.

The result of modulation of a carrier wave by waves of a band of frequencies is to produce two so-called "side bands". See, for example, the article entitled "Carrier current telephony and telegraphy" by Colpitts and Blackwell, pages 307 to 310 inclusive, Journal of the American Institute of Electrical Engineers, Volume 40, April 1921, No. 4. Of these, the upper side band may be considered as the original band of waves having the frequency of each of its components increased by the carrier frequency. Since instead of a high carrier frequency there may be impressed upon the modulator a frequency changing wave of any definite frequency it is obviously possible to increase the effective frequencies of each component of the band by this definite amount. If the

frequency of the wave applied to the modulator is lower than that of the lowest component of the original band, the lower or difference frequency side band resulting from the modulating action may be considered as the original band with its component frequencies each reduced by the definite frequency. There are accordingly available simple methods of stepping up the frequencies of bands of waves or stepping them down at will.

The operation of both modulators and demodulators may be looked upon as that of frequency changers. The modulator operates to change the frequency by the frequency of the so-called "carrier" wave applied thereto. The demodulator in general changes the frequency of a band of modulated wave components by the frequency of the unmodulated carrier wave component which is usually present with the side bands. In both instances upper and lower side bands are produced by the frequency changing operation and it is necessary to select the desired side band by means of filters or other selective circuits.

If in addition to producing the sum and difference frequency components the frequency changer were to transmit components of the original wave frequencies as they occur before combination, there might be confusion if any components of the original waves fell within the same frequency range as the desired combination frequency components or side bands. In order to prevent this, use may be made of modulators and demodulators of the so-called balanced type disclosed and described in connection with Figs. 20 and 49 of the article "Carrier current telephony and telegraphy". The characteristic of these balanced combining devices or frequency changing devices is such that they may be made to substantially prevent transmission of unchanged frequency components and to transmit only components of the combination frequencies.

In order to insure that the frequency increase at the receiving terminal may be the same as the frequency reduction at the transmitting terminal, it is desirable to derive the frequency changing waves at both terminals from a common source which may be located at any convenient point in the system. Where several bands or subbands undergo frequency changes of different amount it is convenient to derive the frequency changing waves from one base frequency wave by harmonic generation. Any well-known system of harmonic generation as, for example, that illustrated and described in connection with Fig. 49 of the article "Carrier current telephony and telegraphy" may be used.

The novel features which are considered characteristic of the invention are pointed

out with particularity in the appended claims. The invention itself, however, both as to the details of its organization and its mode of operation will be best understood by reference to the following description taken in connection with the accompanying drawing in which Fig. 1 illustrates a telephone system particularly adapted for a single loaded cable circuit; Figs. 2 and 3, a telephone system for multiple circuit submarine cable operation; Fig. 4, a detail of the system of Figs. 2 and 3; and Fig. 5 an alternative of this detail.

Referring to Fig. 1, an ordinary telephone circuit 1 is shown connected to a second telephone circuit 2 by means of a cable, loaded circuit, or other toll link 3. The telephone circuit 1 is connected to the cable 3 through a frequency changing apparatus at station A and circuit 2 is connected to the cable by similar frequency changing apparatus at station B. Speech currents originating in or transmitted over circuit 1 may comprise components from very low frequencies up to frequencies of several thousand cycles per second. It is frequently assumed that the essential speech frequency lie within the range of 100 to 2200 cycles. It is of course, possible to transmit intelligible speech by much more limited bands. It is, moreover, not essential that the entire range be retained as portions of it may be omitted without serious loss. An improvement may be made by transmitting certain currents of higher frequencies representing such sounds as the sibilants which are usually poorly transmitted, particularly when circuits of limited frequency transmission range are employed.

Let it be assumed that good quality speech transmission may be had if the bands from 100 to 1000 cycles, 1500 to 2200 cycles and 3600 to 3800 cycles are retained and used. Assume further that the cable or loaded circuit 3 has a transmission range lying substantially entirely below 2150 cycles. The function of the apparatus at station A is to reduce the frequencies of the bands chosen for good quality transmission to such an extent that they may be faithfully transmitted by circuit 3. Speech currents from circuit 1 are supplied by the hybrid coil or balanced transformer 4 to outgoing channel 5 which includes three band filters 6, 7, and 8, having their respective input end sections connected in series. These filters which may be of the type described in the article by Colpitts and Blackwell have transmission frequency ranges, the limits of which are indicated in the drawing. The filter 6 selects its band viz. of 100 to 1000 cycles inclusive, and supplies it directly to bridge circuit 9. A harmonic generator 10 which may be of the type disclosed at Fig. 49 of the article "Carrier current telephony and telegraphy" by Colpitts and Blackwell, supplies oscillations of its base frequency, e. g., 50 cycles, through a low pass filter 11 to circuit 9. The harmonic generator supplies harmonic oscillations of the 50 cycle base frequency wave to an output circuit 40. Any other type of harmonic generator as, for example, that of Fig. 1 of British Patent 131,426 may be employed. Harmonic oscillations of 500 cycle frequency are selected from output circuit 40 by tuned circuits 12 and impressed on a frequency changer or modulator 13 together with the band transmitted by filter 7. One result of the operation of the frequency changer 13 is to produce a band of changed frequency in which the original frequencies of the band passed by filter 7 are each diminished by 500 cycles. This diminished frequency band is selected by band filter 14, the transmission frequency limits of which are indicated in the drawing, and is transmitted to circuit 9. In a similar manner tuned circuits 15 select harmonic oscillations of 1900 cycles which are used at frequency changer 16 to correspondingly reduce the frequencies of the components of the band of currents transmitted by filter 8. Circuit 9 accordingly transmits to cable 3, base frequency oscillations of 50 cycles and a continuous frequency band of currents ranging from 100 to 1900 cycles and thus well within the transmission range of the cable 3.

The currents transmitted to station B are supplied by a hybrid coil 4 to incoming circuit 17 including band filters 18, 19 and 20 and low pass filter 21 having respective end sections in series. The low pass filter 21 transmits only currents of frequency well below 100 cycles, and accordingly selects the 50 cycle base frequency current and supplies it to harmonic reproducer 22 in a manner similar to that described in the article by Colpitts and Blackwell. This harmonic reproducer may be identical in circuit arrangement with element 144 of Fig. 3. Reproducer 22 supplies harmonic oscillations of various multiple frequencies to circuit 23. Tuned circuits 24 select 1900 cycle oscillations and supply them to frequency changer 25 to increase the frequencies of the band of oscillations selected by filter 18 to their original magnitudes and the original frequency subband of 3600 to 3800 cycles inclusive is then separated from resulting currents of other frequencies by filter 26 and supplied to circuit 2. Similarly, 500 cycle oscillations are selected and used to increase the frequencies of the band selected by filter 19 to their original frequency magnitudes. This band is then selectively transmitted by filter 27 to circuit 2. Filter 20 transmits the unchanged band received from filter 6. Each of the various bands is thus restored to its original

nal frequency position and together will yield intelligible speech signals in a telephone receiver associated with circuit 2.

Transmission in the opposite direction, viz., from circuit 2 to circuit 1 is similarly accomplished. Filters 36, 37 and 38 correspond to filters 6, 7 and 8 and serve to separate out three subbands for transmission from the entire range of currents originating in circuit 2. The subband selected by filters 36 is sent direct to line 3. That selected by filter 37 is reduced in frequency by 500 cycles before transmission. The third subband, that passed by filter 38, is reduced by 1900 cycles. The 500 cycle and 1900 cycle currents used to reduce the frequencies of the outgoing bands are selected from the output circuit 23 of harmonic reproducer 22 by tuned circuits. The operation at station A in separating the various subbands received from station B and restoring each to its original frequency position will be obvious from the foregoing explanation. The various harmonic frequency currents necessary for this operation are obtained from the output circuit 40 of harmonic generator 10.

The various elements indicated diagrammatically in Fig. 1, may each be of any desired type, but are preferably of the types illustrated in detail for the corresponding element in the system of Fig. 2.

It will be recalled that in the system of Fig. 1, the characteristic of the transmission circuit 3 and the range of electric waves which are to be transmitted thereover are matched by operation upon the waves to be transmitted. It may happen, as in the case of submarine cables over which speech is to be transmitted, that operation upon the waves in such manner as to retain the elements essential for intelligibility at the distant receiver will not reduce the frequency range to that which can be successfully transmitted by a single submarine cable or other transmission circuit. Figs. 2 and 3 together, illustrate a system adapted to overcome this difficulty. A telephone line 101 terminating at station X is shown connected with a distant telephone line 102 terminating at station Y by means of a system of cable circuits 103, 104, 105, etc. By way of example, it may be assumed that these cable circuits have such transmission characteristics that each of them may be used to transmit currents of a range of 0 to 200 cycles frequency without excessive distortion or prohibitive attenuation. The number of such cable circuits necessary will be dependent upon this transmission range and will increase as the practical transmission band of each circuit decreases. The cable circuits may be metallic or may be "ground return" and the drawing is intended to indicate diagrammatically either type of circuit. Moreover, the conductors of these circuits may be

placed in individual cables or may all be placed in the same cable, depending upon circumstances. The latter form of construction is preferable from the standpoint of economy in the first cost wherever it is permissible from the standpoint of transmission requirements. Each of these cables may be of the periodically loaded (Pupin) or continuously loaded (Krarup) types. Attenuation equalizers may also be employed to counteract the effect of different line attenuations for different frequency components by giving such attenuation to each component that the added attenuations caused by the line and the equalizer are the same for each component. Various attenuation equalizer circuits are well known. Although any desirable type may be used, that preferred in this system and illustrated, is of the type disclosed at Figs. 9 and 10 of U. S. patent to Hoyt No. 1,453,980, dated May 1, 1923. Its advantage as an element of a system in which filters are employed is obvious. It is to be understood that the various receiving circuit devices referred to as band filters, such as 18, 19, etc. in Fig. 1 and the corresponding filters in the system of Figs. 2 and 3 comprise not only frequency selecting elements as in the case of the ordinary band filter, but also elements designed as set forth in the Hoyt patent to give an attenuation complemental to that of the main or toll transmission link.

Line 101 terminates at station X in a net N which simulates its impedance throughout the entire frequency range of the currents transmitted thereover. A hybrid coil or balanced three winding transformer, similar to element 4 of Fig. 1 serves to connect line 101 to incoming and outgoing channels 107 and 108, respectively. Channel 108 is provided with transformers 109, 110, 111, 112, etc., separated respectively by high pass filters 113, 114, 115, etc. Transformer 109 passes outgoing currents from line 101 to a low pass filter which selects those of frequency below 200 cycles and transmits them to line 103. High pass filter 113 readily transmits currents of all frequencies higher than 200 cycles to transformer 110 which supplies them to a band filter having a transmission range extending from 200 to 400 cycles. This band filter impresses its selected band upon frequency changer 120 which is of the same general type as the modulating element illustrated at Fig. 20 of the article "Carrier current telephony and telegraphy."

A harmonic generator 130 of the type illustrated at Fig. 49 of the article "Carrier current telephony and telegraphy" comprising an electric discharge oscillator having coupled input and output circuits and a high resistance element in its space current circuit produces base frequency oscillations of 100

cycles frequency and harmonics thereof and supplies them through a thermionic amplifier also having a high resistance element in its space current circuit to circuit 131 from which tuned circuits 132 select 200 cycle currents for use with frequency changer 120 in reducing the frequencies of the outgoing band transmitted thereby. Frequency changer 120 decreases the frequency of the transmitted subband by 200 cycles. This decreased frequency subband is then selected by a band filter 133 having a transmission range from 0 to 200 cycles and is impressed upon outgoing line 104. Currents transmitted over line 104 are supplied at station Y to a frequency changer 140, which increases the frequency of the received subband by 200 cycles, and this increased frequency subband is then selected by a band filter 150 and impressed upon incoming channel 151 by which it is transmitted to line 102. The frequency changing operation of the device 140 is accomplished by combining the received subband with 200 cycle waves supplied by tuned circuits 141 through an amplifier. Circuit 106 is used to transmit 100 cycle base frequency current from station X to the remote station Y. This current is selected by a low pass filter 143 and is supplied to a harmonic reproducer 144 of any desired type which supplies harmonic frequency currents to its output circuit 145. The harmonic reproducer comprises three electric discharge devices in tandem. The first of these receives the base frequency current and amplifies it to such an extent that the amplified base frequency waves impressed upon the second electric discharge device cannot be faithfully repeated thereby. This produces a distortion of the base frequency waves as repeated in the output circuit of the second electric discharge device and a consequent generation of harmonics thereof. In order to increase the distorting action of the second electric discharge device, it is provided with a high resistance in series with its space current source. The distorted base frequency wave comprising the various harmonics in the output circuit of the second electric discharge device is impressed upon the input circuit of a three element electric discharge device which serves to amplify the harmonics and supply them to circuit 145.

In a similar manner currents originating in line 102 are separated into various frequency subbands each of 200 cycles extent and each subband is reduced to the range of 0 to 200 cycles before transmission to station X. After reception at station X, it is again restored to its original frequency position. It is of course to be understood that the frequency range of the currents transmitted over each individual cable will be determined by the circumstances. Moreover, as

in the system of Fig. 1, certain portions of the speech frequency spectrum may be discarded.

Circuit 106 is associated at station Y with a band pass filter 160 which transmits currents of a narrow band of frequencies including 200 cycles. This circuit serves therefore to transmit back from station Y to station X a return control frequency wave, the amplitude of which at station X will be subject to the same transmission conditions as affect the various message subbands. This 200 cycle wave is selected from circuit 106 at station X by band pass filter 170, identical in character with filter 160 and after selection and amplification is impressed upon a gain control device 171 which is associated with the amplifiers 172, 173, 174, 175, etc., to regulate the gain or amplification of the incoming subbands. The gain control device 200 at station Y is associated with the input circuit 176 of the harmonic reproducer 144 so as to be controlled by the base frequency wave of 100 cycles frequency transmitted from station X.

Fig. 4 illustrates the operation of the gain control element in the system of Figs. 2 and 3. Gain control current of 100 cycles supplied to the input circuit 176 is impressed upon the grid-filament circuit of a three-element electric discharge device 191 which includes a series blocking condenser 177, a polarizing source 178 and a high resistance grid leak 179. The space current in the output circuit of the electric discharge device will be determined in the absence of gain control currents largely by the polarization potential impressed on the grid by source 178. A solenoid having a winding 180 connected in the space current circuit will cause spring retracted plunger 181 to assume a position determined by the strength of this space current. As the gain control current increases, the potential of the grid becomes more negative in the same proportion in accordance with the well-known operation of the grid leak demodulators and the space current falls. As a result of this action, the plunger 181 moves and carries a circuit closer 183 to a position in engagement with a different contact 184. The circuit of the circuit closer may be traced from ground by way of battery 182, circuit closer 183, one of the contacts 184, and a winding of the corresponding relay 185 to ground. The relay 185 which energizes, closes its armature 186, thus determining the portion of the potentiometer resistance 187 to be included in the input circuit of amplifier 188 or 189, as the case may be, and thus to determine the amplification of the subbands received at station Y.

Fig. 5 illustrates a modification of the arrangement of Fig. 4, involving no moving elements. Only so much of the circuits are

- shown as are necessary to explain the application of this modified arrangement to the system of Figs. 2 and 3. In this modification, the input circuit 176 is associated with a plurality of gain control elements 190 one for each of the transmission circuits 103, 104, 105, etc. Element 190 is substantially identical with electric discharge device 191 of Fig. 4, except for the substitution of 10 a resistance network for the solenoid 180 and its associated elements. This network comprises resistances 192 and 193, each of very high magnitude, as of the order of a half megohm, a resistance 194 in shunt 15 thereto and a capacity element 195 which serves as a low impedance for all alternating currents to divert them from the resistance paths. Space current passes mainly by way of resistance 194 which may be of a few 20 thousand ohms to match the internal space current resistance of the device 190. Resistance 193 is of such magnitude as to effectively separate the input circuit of amplifier 188 and the output circuit of gain control element 190 so far as alternating current 25 is concerned. The only action of device 190 will therefore be to impress a direct current E. M. F. across resistance 192. The resistance 192 is included in the polarizing grid-cathode circuit of amplifier 188 in such a 30 manner that the difference of potential caused by the flow of space current therethrough, tends to oppose the polarizing source 196. The result is that the grid 35 potential of amplifier 188 may be only slightly negative or even positive and the amplifying action of the device 188 will be large. As the energy received over circuit 176 increases, the space current of device 40 190 falls and likewise the potential difference across resistance 192. The grid of amplifier 188 therefore becomes more negative and the amplifying action of this amplifier decreases, thus compensating for the 45 increased transmission on circuit 103.
- The transmission of the base frequency current from station X to station Y serves a double function in that it enables the frequency change at station Y to be made exactly the converse of that of station X and moreover, that it may serve to determine the operation of the gain control apparatus.
- In the circuit arrangement of Figs. 2 and 3, the attenuation equalization operation 50 may be combined with the selecting function of the receiving band filters such as filter 150. The ensuing amplification must of course be sufficient to augment the attenuated current, but it should be borne in mind 55 that if the frequency changer is of the electric discharge type illustrated, it introduces an amplification factor.
- Although the invention has been disclosed as embodied in certain specific arrangements, 60 the principles of the invention are obviously

not limited thereto and are capable of application generally.

Certain broad features shown but not claimed herein, relating to transmitting a plurality of non-overlapping frequency subbands over individual transmission circuits, are being claimed in an application of H. A. Affel, Serial No. 532,298, filed January 27, 1922.

What is claimed is:

1. The method of transmitting over a conductor waves having components higher than the practical upper frequency transmission limit of said conductor which comprises utilizing a wave of a single frequency 75 to reduce the component frequencies by a predetermined amount, transmitting said wave of reduced frequency components and said single frequency wave to a distant station, and utilizing said single frequency 80 wave to increase the component frequencies to their original magnitudes.

2. The method of transmitting a broad band of waves which comprises dividing said band into a plurality of subbands, reducing each of said subbands by the frequency of a harmonic of a given base frequency wave, transmitting said reduced frequency subbands to a distant station, transmitting said base frequency wave to said 90 distant station, deriving harmonics of said base frequency wave, and increasing the frequency of each of said subbands by combination with a wave of the same frequency 95 by which it was reduced before transmission.

3. The method of transmitting a broad band of waves which comprises dividing said band into a plurality of subbands, combining each of said subbands with a harmonic of the same base frequency wave to reduce the effective frequencies of said subbands, transmitting said reduced frequency subbands and energy of the base frequency 100 wave to a distant station, deriving harmonics of said transmitted base frequency wave, and combining each of said transmitted subbands with one of said harmonics to restore the subband to its original frequency position.

4. A system for transmitting a band of waves between two stations comprising a source of waves of a definite frequency, means for supplying waves from said source to each of said stations, means for combining waves derived from said source with said band at the first of said stations to reduce the effective frequency of said band, means for transmitting said reduced frequency band to said second station, and means at 110 said second station for combining said received band with waves derived from the waves from said source to restore said reduced frequency band to its original frequency position.

5. A system comprising two separated stations, a source of base frequency currents at the first of said stations, means for supplying base frequency currents therefrom to the second station, means for producing a broad band of waves at the first station, means for dividing said band into a plurality of non-overlapping frequency subbands, means for deriving harmonics of said base frequency wave and reducing the effective frequency of each of said subbands by the frequency of one of said harmonics, means for transmitting each of said reduced frequency subbands to said second station, means at said second station for producing harmonics of the base frequency wave transmitted thereto, and means for combining each of the transmitted subbands with one of said harmonics at said second station to restore said subband to its original frequency position. 35
6. Means for transmitting between two stations a wave having components of a given range of frequencies which comprises means for reducing the frequency of each of said components by a predetermined amount, means for transmitting said reduced frequency components from one station to the other, means at said second station for increasing the frequency of each component of said received wave, means for transmit- 40
- ting between said stations a wave of a definite frequency, and means for causing said definite frequency wave to control the frequency change of said transmitted band. 45
7. A system for two-way transmission between distant points comprising means for transmitting base frequency energy therebetween, means for causing said base frequency energy at each of said points to reduce the effective frequencies of signal energy to be transmitted and to increase the effective frequencies of signal energy received by like amounts. 50
8. A continuously loaded cable circuit, means for transmitting currents of a plurality of frequencies within a range smaller than the effective frequency transmission range of said cable but extending between frequency limits at least one of which is higher than the upper limit of said effective transmission range, and a frequency changing means connecting said transmission means to said cable to reduce the effective frequencies of all of said currents to magnitudes within the limits of said effective transmission range. 55

In witness whereof, I hereunto subscribe my name this 10th day of February A. D., 1922.

ELMER V. GRIGGS.
